UNITED STATES PATENT OFFICE.

SUMNER B. SARGENT AND SUMNER B. SARGENT, JR., OF HUNTINGTON PARK,
CALIFORNIA.PUMPING APPARATUS AND METHOD OF OPERATING THE VALVED PLUNGER OF A
WELL PUMP.

Application filed November 22, 1923. Serial No. 676,286.

To all whom it may concern:

Be it known that we, SUMNER B. SARGENT and SUMNER B. SARGENT, Jr., citizens of the United States, residing at Huntington Park, in the county of Los Angeles and State of California, have invented a new and useful Pumping Apparatus and Method of Operating the Valved Plunger of a Well Pump, of which the following is a specification.

This invention relates to a method for operating the valved plunger of a well pump without the use of sucker rods, and also relates to apparatus by which the method may be performed.

An object of the invention, primarily, is to produce operation of the pump plunger by fluid pressure rather than, as is customary, by the reciprocation of a string of sucker rods.

In many oil fields of the present time drilling for oil is carried to comparatively great depths, often 5000 feet and over. After the flowing of an oil well ceases, it is generally deemed profitable to put the well on the pump. In other words lower a pump into the well and operate it by a string of sucker rods. Such sucker rod operated pumps can be employed successfully in comparatively shallow wells, but it is practically impossible to pump wells that are 5000 feet or more in depth for the reason that the string of sucker rods cannot be made strong enough to sustain their own weight and the weight of the column of liquid above the pump plunger. Increase in the diameter of the sucker rods to increase their tensile strength also increases their weight and the weight of the entire string increases faster than the strength.

To avoid the use of sucker rods in deep wells, we have devised a method of operating the valved plunger which enables us to exert from the top of the well a fluid pressure of sufficient magnitude against one face of the plunger to overbalance the weight of the moving parts and of the column of liquid on the opposite face of the plunger, so as to move the plunger against such weight and thus raise the plunger and liquid, and to then decrease the pressure thus exerted to less than that produced by the weight of the

liquid column and moving parts so as to permit gravity to return the plunger. These operations are repeated at intervals, the frequency of pulsations or number of strokes per unit of time depending upon the degree of pressures and weight of the moving parts. Another object is to provide a construction which will operate efficiently and is simple and not liable to become disarranged and get out of order.

The accompanying drawings illustrate an apparatus built in accordance with the provisions of this invention and capable of performing the various operations of the new method.

Figure 1 is a more or less diagrammatic view of the apparatus, the storage tank being shown in vertical section and the remainder of the apparatus in plan.

Fig. 2 is an elevation, mainly in vertical mid section, of one of the pumping units, being a part of the apparatus shown in Figure 1 but being concealed from view in said figure because of the character of the view.

Fig. 3 is an enlarged sectional elevation of a portion of the pumping unit shown in Figure 2.

Fig. 4 is an enlarged sectional elevation of the lower portion of the pumping unit shown in Figure 2.

Fig. 5 is a plan section on the line indicated by 5—5, Figure 3.

Fig. 6 is a sectional elevation of the upper portion of the pumping unit shown in Figure 2.

Figs. 7 and 8 are plan sections on the lines indicated by 7—7, 8—8, respectively, Figure 6.

Fig. 9 is a typical sectional detail of the construction at the head of each well.

The parts of the apparatus that can be seen in Figures 1 and 9 are as follows: The apparatus may be employed with one or more wells, indicated at 11. In this particular instance seven wells are shown. The tubings are indicated at 12 and are connected with a discharge manifold 13. The manifold 13 is provided on each of its branches with valves 14 and with check valves 15. The manifold 13 is carried to any desired point for discharging the liquid produced

by the wells and, in this instance, it is shown discharging into a storage tank 16.

Each of the wells 11 is provided with another tubing or casing 17 that surrounds the pump tubing 12 and is of sufficiently greater diameter than the pump tubing to produce an annular passage 18, the casings 17 being connected to a liquid supply manifold 19. The manifold branches are provided with manually operated valves 20, check valves 21 and suitable pressure regulated valves 22.

The manifold 19 connects with means for producing variation in the fluid pressure within the tubing 19, said means, in this instance, being in the form of a pump 23 operated by steam or any other motive power. In this instance the steam chest of the pump 23 is indicated at 24 and the piston rod at 25 and the pump 23 is connected by a pipe 26 to any suitable source of liquid supply which, in this instance, is the storage tank 16.

The constructions in the different wells are alike and, therefor, only that in one of the wells need be described in detail and such construction is illustrated in Figures 2 to 8 inclusive and is as follows:

The pump tubing 12 hereinbefore mentioned is connected by a suitable coupling 27 to a working barrel 28 which, in this particular instance, is formed in sections connected by a coupling 29, which is screw-threaded into the adjacent ends of the working barrel sections. The working barrel 28 is provided below the coupling 29 with a port or ports 30 which communicate with the annular passage 18.

Mounted in the working barrel 28 is a plunger comprising end portions 33, 34 of smaller diameter and an intermediate portion 35 of larger diameter. The plunger portion 34 slides through the working barrel portion 36 of reduced inside diameter, and the plunger portion 33 slidably fits in the coupling 29. It will be seen that the annular space 37 between the coupling 29 and plunger portion 35 constitutes a chamber whose cubical content varies according to the position of the plunger, and that the annular space 38 between the plunger portion 35 and the barrel portion 36 constitutes a chamber whose cubical contents also vary according to the position of the plunger. The ports 30 communicate with the chamber 38, and a port or ports 39 in the plunger above the portion 35 open from the plunger into the chamber 37. The plunger is valved, being provided in this instance at its upper end with a valve 40 which may be of any suitable construction such as is well known in this art.

The plunger portion 34 also slidably fits in an externally tapered bushing 41 which engages the tapered seat 42 of a coupling

43 that serves to unite two sections of the tubing 17. The bushing 41 is screw-threaded into the lower end of the working barrel 28 or an extension thereof.

The construction hereinbefore described is sufficient to constitute an operable apparatus for effecting the pumping operation, the method of operating the valved plunger being as follows: A fluid pressure of sufficient magnitude is exerted from the top of the well in the chamber 38 against the face 44 of the plunger to overbalance the weight of the moving parts and of the column of liquid on the opposite face 45 of the plunger to move the plunger against such weight and thus raise the plunger and said column. This is accomplished by operating the pump 23 which pumps liquid from the storage tank 16 through the supply manifold 19 and tubing 17 so as to force the operating fluid through the annular space 18 and ports 30 into the chamber 38 and against the plunger face 44. The in stroke of the pump 23 accomplishes this.

The next step in the operation is to decrease the pressure of the operating fluid to less than the pressure produced by the weight of the moving parts and column of liquid that is being pumped to permit gravity to return the plunger. This is accomplished by operation of the pump 23 on its out stroke. Thus, the pulsations of the operating fluid effected by operation of the pump 23 are transmitted to the plungers of the pumps in the various wells. It will be readily understood that, when the plunger 33, 34, 35 operates on its up stroke, liquid within the chamber 37 will be expelled therefrom through the ports 39 into the bore of the plunger.

The usual standing valve, not shown, is provided at the lower end of the working barrel and as the plunger rises on its suction stroke said standing valve opens to admit fluid to the working barrel and the valve 40 closes, thus effecting lifting of the liquid column above the plunger in a manner well understood in this art. The plunger having reached the end of its suction stroke begins to descend because of the reduction in pressure of the operating fluid against the plunger face 44. To obtain this result the plunger area upon which the liquid above the valve 40 acts will be greater than the area of the plunger face 44. The valve 40 remains closed until the pressure beneath said valve becomes greater than that above the valve which then opens, thus balancing these pressures. The inertia of the downwardly moving plunger is a force that will continue to be exerted after the valve 40 opens, and this force is supplemented by the weight of the moving parts, which weight is of sufficient magnitude to overbalance the pressure of the operating fluid

against the plunger face 44. It may be advisable to increase the effect of gravity by adding the desired number of loose weights to the plunger, as will be more fully explained hereinafter, thus to increase the speed of the plunger on its suction stroke.

The different wells may require different pressures of the operating liquid due to various conditions such, for example, as the 10 depth of the wells or the gas pressure therein and, accordingly, the pressure regulated valves 22 will be adjusted to permit the operating liquid to flow into the different wells at the pressure that is discovered to be right 15 for effecting peak production or less, as desired.

Though the above described apparatus constitutes a complete operating assembly, it is desirable to provide a check valve in the 20 pump tubing to prevent back flow of the liquid being pumped when the plunger operates on its down stroke, thus to avoid the necessity of raising the column of liquid the 25 distance that it would have descended with the plunger were the check valve not present. A suitable check valve for this purpose is indicated at 45 and may be of any desired construction. In this instance the check 30 valve 45 is mounted in a slightly tapered seat 46 in the coupling 27 and comprises a seat member 47 tapered externally to engage the seat 46, and a valve 48 to engage a tapered seat 49 formed in the seat member 47. The 35 taper of the seat 46 is much less than that of the seat 47 so that the seat member 47 will remain stationary when the valve 48 opens. The valve 48 is operated by a rod 50 which may be considered to be a reduced portion of the plunger and which connects with the 40 cage 51 of the valve 40 and extends through packing 52 in the valve 48. The valve cage 47 is provided with openings 53 and is of less diameter than the inside of the pump 45 tubing so that liquid can flow freely through said openings. As the plunger operates on its down stroke, the valve 48 will be retained on its seat and, as the plunger moves upwardly, the valve 48 will be raised by the rod 50 until said valve strikes the upper end 50 of the valve cage 47. As the pump plunger continues on its up stroke the rod 50 will slide through the packing 52 and then, during the first part of the down stroke of the plunger, the rod 50 will actuate the valve 48 into closed position upon the seat 49. This limited lift of the valve 48 is necessary 55 in order to close quickly to accomplish the purpose for which it is placed in the pump tubing.

60 It has been hereinbefore stated that the check valve 45 can be omitted, in which event the weight of the moving parts and of the column of liquid above the plunger, resting upon said plunger, would function initially 65 to return the plunger when said weight over-

balances the pressure of the operating fluid. However, when the check valve is employed, said check valve, closing, prevents the weight of the raised liquid column from coming effectively upon the valve 40 and, consequently, the down stroke of the plunger 70 would not be aided under such conditions unless the plunger were extended through the check valve into the space above said valve. In order to return the plunger, the 75 upper end of the rod 50 is provided with an enlarged plunger portion having in its interior a valve seat 55 for an upwardly opening ball check valve 56. The liquid that is raised by the upstroke of the pump plunger 80 passes the check valves 45, 56 and enters the pump tubing above the plunger portion 54. When the pressure of the operating fluid is subsequently decreased, the overbalancing 85 weight of the moving parts and of the liquid column upon the plunger portion 54 thrusts the pump plunger on its down stroke.

The weight of the moving parts may be increased by the addition of loose weights, as hereinbefore referred to and a number of 90 these are indicated at 57, being mounted upon a stem 58 that projects from the top of the valve cage 54.

It will be readily understood that the 95 valve 56 cannot be used in lieu of the valve 45, because the valve 56 will not close until the pump plunger reaches the lower end of its stroke, whereas the valve 45 closes shortly after the pump plunger begins its down stroke, due to the rod 50 frictionally engaging 100 the packing 52.

We claim:

1. A pumping apparatus for wells comprising a working barrel having a port and having a portion of its bore reduced in diameter adjacent to the port, a tubular member surrounding the working barrel and spaced therefrom to form a passage, means to close the lower end of the passage, and a tubular valved plunger in the working 105 barrel having a reduced portion slidably fitting the reduced bore portion, the reduced portion terminating in a pressure face acted upon by fluid admitted through the port and said pressure face being of less area 110 than the area of the upper end of the plunger.

2. A pumping apparatus for wells comprising a working barrel, a plunger in the working barrel, means extending to the top 120 of the well to produce a greater fluid pressure against one face of the plunger than that resulting from the weight of the moving parts and liquid column on the plunger and to then decrease the first pressure, and an upwardly opening check valve in the pump tubing, the plunger having a valve cage below the check valve and a valve in 125 said cage, the plunger having a reduced portion passing through the check valve, the 130

plunger having an enlarged portion above the check valve and having an upwardly opening valve in said enlarged portion.

3. A pumping apparatus for wells comprising a working barrel having a port and having a portion of its bore reduced in diameter adjacent to the port, a tubular member surrounding the working barrel and spaced therefrom to form a passage, means to close the lower end of the passage, a tubular valved plunger in the working barrel having a reduced portion slidably fitting the reduced bore portion, the reduced portion terminating in a pressure face acted upon by fluid admitted through the port and said pressure face being of less area than the area of the upper end of the plunger, and an upwardly opening check valve in the pump tubing, the plunger having a valve cage below the check valve and a valve in said cage, the plunger having a reduced portion passing through the check valve, the plunger having an enlarged portion above the check valve and having an upwardly opening valve in said enlarged portion.

4. A pumping apparatus for wells comprising a working barrel having a port and having a portion of its bore reduced in diameter adjacent to the port, a tubular member surrounding the working barrel and spaced therefrom to form a passage, means to close the lower end of the passage, a tubular plunger in the working barrel having a reduced portion slidably fitting the reduced bore portion, the reduced portion terminating in a pressure face acted upon by fluid admitted through the port and said pressure face being of less area than the area of the upper end of the plunger, said plunger having cages with openings and upwardly opening valves in the cages and having a reduced portion connecting the cages, and a check valve positioned in the pump tubing between the plunger valves and operably connected with the plunger.

Signed at Los Angeles, California, this 10th day of November, 1923.
